UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

WIRELESS RECEIVING SET.

Application filed July 11, 1922. Serial No. 574,816.

My invention relates to wireless telegraphy and particularly to circuits and apparatus adapted for embodiment in wireless receiving sets.

5 One object of my invention is to provide a cabinet of simple, compact and rugged design adapted to embody a complete radio-receiving set which is characterized by its extreme simplicity of operation and the absence of complicated adjustments.

Another object of my invention is to provide a wireless receiving set of such design as to admit of inexpensive quantity production with existing manufacturing methods.

15 Still another object of my invention is to provide a receiving system embodying antenna and detector circuits wherein extremely sharp tuning of the antenna circuit may be effected without decreasing the efficiency of the detector circuit.

20 In order to obtain sharp tuning in the antenna circuit, it is necessary that the circuit have a relatively large amount of inductance and a relatively small amount of capacitance.

25 If the antenna inductance and capacitance constants are adjusted as just mentioned, as by means of a variometer having a large inductive reaction and a condenser having a large capacitive reaction, and the detector circuit is connected in shunt relation to the variometer, optimum operating conditions are not obtained, since the energy loss in the antenna circuit and the detector circuit 30 are, in general, not equal.

According to my invention, I provide a circuit arrangement adapted to obviate the above-mentioned difficulties, wherein the detector circuit is connected across a predetermined portion of the variometer winding, as determined by the specific values of the antenna and detector circuit constants.

40 My invention further consists in the provision of a unitary structure or box adapted to contain the wave-responsive apparatus of a wireless receiving system. The box is provided with two main compartments, one of which is open at the top and adapted to removably contain accessory apparatus, as, 45 for instance, a telephone device. The other

compartment is provided with a control panel constituting a top cover for the compartment. The control panel may also serve as a support for the wave-responsive apparatus in a manner hereinafter described. 55 A movable lid may be provided for the box enclosing a space between itself and the control panel.

Other objects of my invention, as well as details of construction and circuit arrangement, whereby my invention may be practised, will be apparent from the following description, when taken in connection with the accompanying drawings, wherein:

55 Figure 1 is a diagrammatic view of circuits and apparatus embodying my invention;

60 Fig. 2 is a top plan view of the unitary structure or box adapted to contain the circuits and apparatus, except the antenna and the ground connection, shown in Fig. 1.

65 Fig. 3 is a side elevational view, shown partially in section on the line III—III of Fig. 2, with the cover removed.

70 In Fig. 1 is shown a wireless receiving system 1 adapted for embodiment in a unitary structure or box 2, as shown in Figs. 2 and 3. The receiving system 1 comprises an antenna circuit 3 and a detector circuit 4 operatively associated therewith. The 75 antenna circuit 3 comprises an antenna 5, a down lead 6, a wave-changing arrangement 7, a variometer 8 having relatively stationary and movable coils 9 and 11, respectively, a ground binding post 12 and a ground conductor 13 therefor.

80 The wave-changing mechanism 7 comprises a pair of serially connected condensers 14 and 15, one terminal of the pair being connected by a flexible conductor 16 to one end of the movable variometer element 11. A pair of binding posts 17 and 18 are connected to the remaining terminal of said pair of condensers and to a point intermediate the same to provide relatively 85 short or long wave connections for the antenna down lead 6. The detector circuit 4 extends from the ground terminal 13 to a tap point 19 on the stationary coil 9 of the variometer 8 and includes a detector 21 and 90 100

a pair of binding posts 22 and 23 to which are connected, in shunt relation, a telephone receiver 24 and a by-pass condenser 25.

A dial plate 26 for indicating the relative

positions of the variometer coils, as herein-after more fully explained, is connected to ground by means of a conductor 27.

The unitary structure or box 2 is adapted to contain the circuits and apparatus of Fig. 1 included between the antenna binding posts 17 or 18 and the ground binding post 12 comprises a substantially rectangular chamber 28 open at the top. The chamber 28 may be divided into two compartments 29 and 31 by means of a vertically positioned partition extending from the front side 33 of the box 2 to the rear side 34 thereof. The compartment 29 contains the telephone receivers 24 or other apparatus associated with the receiving system, when the set is not in use. A control panel 35 constitutes the top cover for the other compartment 31, opposite parallel edges of the cover being supported by means of the partition 32 and a supporting ledge 36 on the side wall 37 of the box 2.

The stationary coil 9 of the variometer 8 is mounted upon a cylindrical form 38 which is by an element 40 supported at a point on the under surface of the panel substantially centrally disposed. The movable element 11 of the variometer 8 is mounted on a cylindrical form 39 which is adapted to be rotatably mounted at its upper end by means of a rod 41 rotatably carried by the dial plate 26 which is disposed upon the top surface of the control panel 35. A handle member 43 comprising oppositely extending portions 44 and 45 is secured to the upper end of the rod 41. The handle portion 44 is adapted to serve as actuating means for the rotatable element 11 of the variometer 8 while the remaining handle portion 45 is adapted to serve as a pointer for the dial 42. A centering rod 46 extends through the lower portions of the two cylindrical forms 38 and 39 and is designed to provide a lower bearing for the movable form 39.

The detector 21 is mounted on the top side of the panel 35. The wave-changing condensers 14 and 15 are embodied in a single structure 47 mounted on the under surface of the panel. An insulating block 48 may be frictionally carried by the pivot rod 41. The block 48 is provided with a perforation 49 receiving the connection 16 between the condenser structure 47 and the movable element 11 of the variometer 8, as illustrated in Fig. 3, the connection 16 passing through an enlarged opening in the cylindrical form 38, coaxial with the block 48. The antenna wave-changing binding posts 17 and 18, the ground binding post 12 and the telephone binding posts 22 and 23 are mounted upon the top side of the panel 35 and adjacent to the rear wall 34. The telephone by-pass

condenser 25 is mounted at a point on the under surface of the panel 35 immediately adjacent to the telephone binding posts 22 and 23.

A screw member 51 which serves to bind the dial plate 26 to the top surface of the panel 35 may also serve as a circuit terminal for the dial-plate ground connection 27 illustrated in Fig. 1. The advantage of grounding the dial plate 26 is to cause the same to serve as a shield, thereby ensuring protection against capacity effects attendant with the presence of an operator. A movable lid 52 may be connected to the rear wall 34 and provides an enclosed space between the control panel 35 and itself when in a closed position, thereby providing a protective covering for the instruments mounted on the top side of the panel 35.

In operation, assuming the antenna connected to either the short-wave or the long-wave circuit terminals 17 and 18, and the ground conductor 13 connected to the ground terminal 12, the system may be adjusted to resonance to incoming signal impulses by moving the handle 44 of the variometer 8, as will readily be understood by those skilled in the art.

While I have described a specific embodiment of my invention for the purpose of illustrating the objects, advantages and applications thereof, it is apparent that various changes and modifications may be made in the circuit arrangements and details of construction without departing from the spirit and scope of my invention. I desire, therefore, that only such limitations shall be imposed thereon as are specifically set forth in the appended claims or demanded by the prior art.

I claim as my invention:

1. An oscillatory circuit having relatively large capacitive reactance to currents of predetermined frequency, a variable inductor having a relatively large reactance to currents of predetermined frequency, said inductor comprising relatively stationary and relatively movable coils, said coils being connected in series, and indicating means connected across a predetermined portion of and adapted to derive energy from said stationary coil, said predetermined portion being such that the energy losses in said indicating means are substantially equal to the energy losses in said oscillatory circuit.

2. In a variometer, a tubular form provided with windings constituting the stationary element of said variometer, a second tubular form disposed within said first-mentioned tubular form and of such dimensions as to admit of turning the same therein and provided with windings constituting the movable element of said variometer, a supporting rod having one end secured to said second form, means for rotat-

ably mounting the other end of said rod in such manner that said second form may be carried thereby, an insulating block secured to said rod and provided with a perforation extending to the lateral surface thereof, and a flexible terminal lead of the movable element of the variometer, said lead extending from said movable element through the perforation in said insulating block, whereby said block may serve as a support for said lead.

In testimony whereof, I have hereunto subscribed my name this 5th day of July, 1922.

FRANK CONRAD.
